UNITED STATES PATENT OFFICE.

THOMAS ANDREW JACKSON WHEELER, OF IVANHOE, TEXAS.

DESIGN FOR A JACK-SCREW STAND AND LIFTER.

42,378.

Specification for Design. Patented Mar. 26, 1912.

Application filed October 6, 1911. Serial No. 653,292. Term of patent 14 years.

To all whom it may concern:

Be it known that I, THOMAS A. J. WHEELER, a citizen of the United States, residing at Ivanhoe, in the county of Fannin and State of Texas, have invented a new, original, and ornamental Design for a Jack-Screw Stand and Lifter, of which the following is a specification, reference being had to the accompanying drawing, forming part thereof.

Figure 1 is a side elevation; and Fig. 2 a perspective view.

I claim:

The ornamental design for a jack screw stand and lifter, as shown.

THOMAS ANDREW JACKSON WHEELER.

Witnesses:

J. L. DOBBS,
S. C. CORTON.
